UNITED STATES PATENT OFFICE

2,174,038

HEAT EXCHANGE STRUCTURE

Carl E. Meyerhoefer, Brooklyn, N. Y., assignor to
E. A. Laboratories, Inc., Brooklyn, N. Y., a corporation of New York

Original application August 12, 1937, Serial No. 158,669. Divided and this application November 24, 1937, Serial No. 176,180

4 Claims. (Cl. 257—137)

This invention relates to a structurally and functionally improved heat transfer unit, and in its more specific aspects, aims to provide an article of this character which will be ideally suited for use in connection with the interiors of vehicles; this application being a division of my previous application for patent, Serial No. 158,669 on heater and fan construction, filed in the United States Patent Office on August 12, 1937.

It is an object of the invention to furnish a heat transfer mechanism—and especially a unit to be employed as a heater—which mechanism will embody relatively few parts, each individually simple and rugged in construction and capable of production and assembly largely by automatic machinery and unskilled labor.

A further object of the invention is that of constructing a unit of this type, and by means of which a large volume of air may be effectively distributed.

An additional object is that of providing a structure for use in connection with a heat transfer unit such that the parts of the unit may readily be manufactured and assembled with minimum expense and in order to furnish a most desirable structure.

With these and other objects in mind, reference is had to the attached sheets of drawings, illustrating practical embodiments of the invention, and in which:

Fig. 1 is a sectional plan view taken through a complete heat transfer unit, but showing the core, fan and motor casing in elevation;

Fig. 2 is a rear view of the unit as illustrated in Fig. 1 and taken along the lines 2—2 and in the direction of the arrows of that figure; it being, moreover, noted that certain of the parts have been broken away to disclose underlying constructions;

Fig. 3 is a fragmentary perspective view of a portion of the heater assembly; and

Fig. 4 is a view similar to Fig. 2, but illustrating a slightly different form of construction.

Referring primarily to Figs. 1 and 2, it will be observed that the numeral 10 indicates a heating core, including for example, spaced heads between which a heat transfer structure extends. This structure may take numerous different forms but preferably, and for the purpose of the present specification, is to be considered as a cellular type radiator, extending from the heads are tubes 11, which may be connected with the circulating system of the engine of a motor vehicle, or otherwise. In any event, hot or cold fluid is circulated

through these tubes and through the heat transfer core. The edges of the core are enclosed by a main casing 12, and this casing extends rearwardly of the core. The entire unit may be mounted by means of brackets 13. Directly or indirectly coupled to these brackets is a motor mounting plate or web 14 supporting a motor casing 15. The shaft 16 of this motor has attached to it an air impeller, as for example by hub 17 and set screw 18.

A shroud plate assembly is formed by telescoping and seaming within the main casing 12 a further casing section comprising a rear wall plate 21 formed with a central annular opening and a flange 22. This flange 22 is preferably continued to form mounting arms 19 to receive or support resilient studs 19' which bear against and retain the core assembly in position within and adjacent the forward portion of the casing 12. If desired, the mounting arms 19 may be 20 separate plates or any other convenient structure.

Secured forward of and spaced from the rear wall plate 21 are a pair of flanged plates 20, each presenting arcuate inner edges and cooperating to form a central annular opening of a greater area than the opening in the rear plate 21. The plates 20 may be conveniently attached to the inner face of flange 22.

Now with regard to the air impeller, it will be understood that this primarily forms the subject matter of my previously filed application of which the present is a division. Suffice it to say that such air impeller may conveniently include (Figs. 1 and 2) a plurality of fan blades 31 attached, for example, to an annular strip 24 but being spot welded or otherwise secured to inwardly extending portions 30 forming a part of such strip. To provide such portions strip 24 may be slotted as indicated at 29. This strip also carries integrally or otherwise a blower wheel comprising a plurality of blades 28 and it is obvious, as a consequence of this structure, that when the motor is operating, air will be drawn through the heat transfer unit and be distributed rearwardly by fan blades 31 and outwardly through the space between plates 29 and 21 by the blower wheel structure.

The form of air impeller illustrated in Fig. 4 follows substantially the same teachings as heretofore, excepting that as taught in the prior application the fan blades are preferably formed integrally with the blower wheel. Accordingly, it will be most desirable to have the fan draw cold air through its body and impel the same out.

wardly through the heat transfer core while air is sucked through such core and then distributed by the blower wheel structure.

However, in any instance where air is sucked 5 rearwardly or inwardly and is thereupon to be distributed through the interior or space to be heated or cooled, a structure having the functional characteristics such as those included in my prior Patent No. 2,087,160, issued July 13, 1937, 10 may be employed.

Now with a view to distributing the air discharged by the blower wheel, it will be observed, as in Fig. 2, that ducts 32 may extend from each corner of the main casing and afford passages 15 which may be conveniently coupled to the tubes, or otherwise, which latter are connected, for example, to openings or nozzles situated adjacent the windshield, or other desired portion of the vehicle. A distinct advantage is, of course, derived by the use of individual ducts and the inner ends of these ducts, or passages, may conveniently be provided in the following manner:

As shown in Figs. 2 and 3, the flange 22 of the shroud plate assembly is slotted to furnish a 25 tongue portion 33 and the latter is bent inwardly to extend at a tangent to the elements of the blower wheel. In line with the opening thus furnished, the main casing is cut away, and in fact the opening furnished through the latter should, 30 preferably, be of larger area than the opening through flange 22. A duct 34 of rectangular or other configuration, overlies flange 22 and provides a passageway in line with the opening through the latter. This duct extends flush with, 35 and forms a continuation of, main casing 12. Consequently, properly extending discharge passages are furnished for the air which is radially distributed by the blower wheel.

In many respects it is preferred to have these 40 passages extending outwardly from the side edges of the casing, but if a greater "pick-up" space is desired for the blower wheel, and in advance of these passages, then they may be located as shown in Fig. 4. In this figure a construction identical 45 to that afore described is employed with the exception only that the passageways extend perpendicularly to the longitudinal edges of casing 12. However, it will be apparent that under these 50 circumstances practically the entire effective space between one passageway and the next adjacent passageway may be employed by the blower wheel to collect air for discharge through such passageways. Obviously, while it is desirable to employ a pair of discharge passages, a 55 greater or lesser number of the same might be utilized.

As a consequence of a construction such as the foregoing, it will be understood that it is feasible to provide and form sheet metal parts which may 60 readily be assembled to furnish a unitary structure which will be rigid and rattle-proof. Aside from this advantage, however, such structure will permit of a most efficient distribution of air aside from the fact that it is feasible to employ this 65 structure in quantity production methods which will necessitate only such skill as an ordinary workman possesses.

Thus, among others, the several objects of the invention, as afore noted, are achieved. It will

be understood that numerous changes in construction and method and rearrangement of the parts might be resorted to without departing from the spirit of the invention as defined by the claims.

Having described my invention, what I claim as new and desire to secure by Letters Patent is:

1. A housing to receive a heat exchange structure and including a casing presenting a corner portion, said casing being slitted and bent to furnish an inwardly extending tongue adjacent such corner portion and providing in association with said casing the entrance to a duct and a duct member applied to said casing and overlying the opening, thus provided, to furnish a continuation 10 of said duct extending angularly with respect to said casing.

2. A housing to receive a heat exchange structure and including a pair of casings, one enclosing the other of the same, the innermost of said casings being slitted to provide a tongue portion, said tongue portion being bent to extend angularly with respect to the wall of said casing to furnish a duct entrance, the outermost of said casings being formed with an opening of an area 20 larger than the opening provided by said tongue and in line with such opening and a duct member presenting flanges to overlie the surface of said innermost casing, the edges of said flanges substantially abutting the edges of the outer casing opening.

3. A housing to receive a heat exchange structure and air distributing mechanism, said housing including a shroud plate assembly comprising a pair of substantially identical and flanged plates disposed adjacent each other and providing in aggregate an annular opening, a casing also forming a part of said assembly and secured to said flanges and providing in association with said plates a housing for a blower wheel, said casing including a flange, and a rear wall plate formed with a central opening of an area less than the opening provided by said first named plates, a fan in said last mentioned opening, a main casing forming a part of said housing and enclosing said first named casing and secured thereto to maintain the latter in position, and inwardly extending mounting portions forming a part of said first named casing to support a heat exchange unit within said main casing and 50 beyond said first named casing.

4. A housing to receive a heat exchange structure and air distributing mechanism, said housing including a main casing, a pair of substantially identical flanged plates, disposed adjacent each 55 other and within said casing, and cooperating to form an annular air distributing opening, a further casing telescoped within said main casing and having inwardly extending mounting portions disposed in front of said plates for supporting a heat exchange structure in front of said opening and within said main casing and a wall rearwardly of said plates and providing in association with said plates, a blower housing, said wall being formed with a central fan receiving 60 opening, and said main and telescoped casings being formed with aligned openings cooperating 65 to form an outlet for said blower housing.

CARL E. MEYERHOFER.
